UNITED STATES PATENT OFFICE.

WALTER E. HUCK, OF ROSCOE, SOUTH DAKOTA.

PLOW.

1,073,759.

Specification of Letters Patent. Patented Sept. 23, 1913.

Application filed March 20, 1912. Serial No. 685,009.

To all whom it may concern:

Be it known that I, WALTER E. HUCK, a citizen of the United States, residing at Roscoe, in the county of Edmunds and State of 5 South Dakota, have invented a new and useful Plow, of which the following is a specification.

This invention relates to plows and more particularly to a plow attachment having 10 means whereby the point or body of the plow will be automatically released when said plow is brought into contact with an unyielding obstruction in its path, there being means for automatically returning the 15 plow point to its proper position relative to the beam and to its proper depth in the soil after passing over the obstruction, such elevation and return of the plow point being effected without interfering with the proper 20 operation of the mechanism employed for adjusting the plow vertically.

With the foregoing and other objects in view which will appear as the description proceeds, the invention resides in the combination 25 and arrangement of parts and in the details of construction hereinafter described and claimed, it being understood that changes in the precise embodiment of the invention disclosed can be made within 30 the scope of what is claimed, without departing from the spirit of the invention.

In the accompanying drawings the preferred form of the invention has been shown.

35 In said drawings:—Figure 1 is a side elevation of the plow, the positions of the parts when the point is elevated, being indicated by dotted lines, portions of the structure being broken away. Fig. 2 is a plan view of 40 a portion of the beam. Fig. 3 is a perspective view of the pawl. Fig. 4 is a side elevation of a portion of the beam and the pivoted sections in the positions assumed thereby when the plow share is elevated.

45 Referring to the figures by characters of reference 1 designates a beam having its rear end portion reduced transversely to form a tongue 2 which projects between parallel arms 3 extending forwardly from a shift- 50 able beam section 4 the rear end portion of which is slotted as at 5, to receive the head 6 of a standard 7 to which the plow share 8 is connected. Said head 6 is pivotally mounted within the slot 5, as shown at 9 and 55 has a forwardly extending tongue 10 overhanging the beam section 4 and provided

with a stop screw 11 which can be adjusted so as to vary the angle of the standard 7 to the beam section 4.

The rear end of the tongue 2 is cut away 60 at its lower corner to form a recess 12 adapted to receive a roller 13 formed at one end of a plunger 14. The top of this recess is sloped slightly upward and backward. This plunger is mounted to slide within a recess 65 15 in the lower face of the beam section 4 and is retained in the recess in any suitable manner, as by means of a plate 16. A spring 17 is interposed between the plunger 14 and the end wall of the recess 15 and serves to 70 hold the roller 13 normally projected beyond the open end of the recess. A stop pin 18 is arranged in the recess 15 and projects into a groove 19 in the plunger, this pin serving to limit the sliding movement of the plunger. 75 When the roller 13 is seated in recess 12, the section 4 is held in alignment with the beam 1, downward movement of the section 4 relative to the beam being prevented by the ends of the arms 3 abutting against the shoulders 80 formed at the front end of the tongue 2, as shown at 20. A lifting finger 21 is secured to one of the arms 3 close to the pivot bolt 22 which extends through the arms and the tongue 2 and this finger is normally located 85 above the plane of the upper faces of beam 1 and section 4, as indicated by full lines in Fig. 1. One side of the beam 1 is cut away as at 23 so as to permit the finger 21 to swing downwardly when the section 4 is 90 swung upwardly about the pivot 22.

Secured on the beam 1 at one side of the finger 21 is a longitudinally extending ratchet bar 24 adapted, under certain conditions, to be engaged by a pawl 25 pivotally 95 connected to an arm 26 extending upwardly from the fulcrum 27 of a gage lever 28. This lever extends downwardly from the beam 1 at a point in front of the plow share 8 and may carry a gage wheel 29. An equalizer bar 30 is pivotally connected to the upper end of arm 26 and is pivotally and slidably connected, at its upper end, to a rod 31 extending forwardly to a lever 32 to which it is pivotally connected. This lever is fulcrumed, as at 33, upon the front portion of beam 1 and carries a pawl 34 adapted to engage a toothed segment 35 and thus hold the lever 32 against movement. 105

A rod 36 is pivotally and slidably connected to the lower end of the equalizer bar 30 and pivoted to a bracket 37 mounted 110

on the arms 3. Another bracket 38 is secured to the tongue 2 and extends downwardly therefrom and said tongue has a slot 39 above bracket 38. A rod 40 is connected, at its lower end, to the bracket 38 and is adapted to swing relative thereto, this rod being extended through the slot 39 and being also extended slidably through the bracket 37. A spring 41 is mounted on rod 40 and bears downwardly on bracket 37 and upwardly against an adjusting nut 42 engaging rod 40.

It is to be understood that beam 1 is to be hingedly connected to the frame A or other structure drawing the plow so that it is thus possible for the rear portion of the beam and the parts connected thereto to be raised and lowered. The gage wheel 29 travels on the ground all of the time and carries the weight of the plow.

By means of lever 32 movement may be transmitted through rod 31 to equalizer 30 and the vertical adjustment of the plow is thus effected. When arm 26 is swung forward by the forward movement of the equalizer 30, wheel 29 is moved backward, thereby raising the beam 1. As wheel 29 is constantly in contact with the ground and constantly supports the weight of the plow, it will be apparent that arm 26 continuously bears backwardly against the equalizer 30. The plow remains in the position to which it has been adjusted until the point or share comes into contact with an unyielding obstruction whereupon the sudden jolt thus produced causes roller 13 to move back into recess 15 and thus release the section 4. The forward motion of the beam 1 and other parts causes the section 4 to swing upwardly while the point remains in contact with the obstruction, and during this upward swinging motion of the section 4 bracket 37 is carried forward and causes the nut 36' on rod 36 to press on the equalizer bar 30 which is pivoted to arm 26. Said arm 26 will thus be swung forward and cause the gage wheel arm 28 to swing downwardly relative to the beam as indicated by dotted lines in Fig. 1, thereby elevating the beam 1 by swinging it on its hinge connection with the structure in front of the beam and which has not been shown. During this movement pawl 25 shifts into engagement with the rack 21 and holds the arm 26 against movement relative to the beam 1 and, therefore, holds the beam 1 tilted upwardly and rearwardly. It is to be understood of course that this elevation of the rear end of beam 1 continues until after the point of the plow share has passed over the obstruction. As soon as the obstruction has been passed the spring 41 operates to bring the section 4 back to its position in alinement with beam 1 whereupon plunger 14 reenters the recess 12. As

soon as section 4 comes in alinement with beam 1 the finger 21 lifts pawl 25 out of engagement with the ratchet bar 24, thereby releasing arm 26. As soon as arm 26 is released, the weight of the beam 1 and the parts connected thereto will cause said beam to lower and arm 26 will thus be free to swing backwardly relative to the beam, the equalizer bar 30, at the same time, moving along the rods 31 and 36 until it assumes its normal position thereon. Thus it will be seen that as the beam 1 is lowered in this manner the plow is brought back to its former depth in the soil and the parts are reset so as to operate again in the manner hereinbefore described.

While the mechanism constituting the present invention has been shown and described applied to one form of plow construction, it is to be understood that the location of the several parts can be varied so as to adapt said part to plows of other constructions. Furthermore instead of using a gage wheel, any other suitable means may be employed to lift and hold the plow at a certain elevation and thus actuate the mechanism and accomplish the same result as that heretofore described, to wit, automatically lifting the plow and holding it in elevated position until the plow share passes over the obstruction in the path thereof whereupon the parts will be automatically returned to their normal positions.

Although only a single rod 41 has been shown, it is to be understood that two of these rods may be used if so desired.

What is claimed is:—

1. A plow including a beam, a section pivotally connected thereto and movable upwardly relative to the beam, a plow share connected to and movable with said section, coöperating means upon the beam and section for normally holding the section in alinement with the beam, said holding means being shiftable to release the section when the share contacts with an unyielding obstruction, and means supported in front of the share and shiftable by the section, when released, for elevating the beam and share.

2. A plow including a beam, a section pivotally connected thereto and movable upwardly relative to the beam, a plow share connected to and movable with said section, coöperating means upon the beam and section for normally holding the section in alinement with the beam, said means being shiftable to release the section when the share contacts with an unyielding obstruction, soil engaging means supported in front of the share, means operated by the section when released, for bearing downwardly on said soil engaging means to elevate the beam and share.

3. A plow including a beam, a section pivotally connected thereto and movable upwardly relative to the beam, a plow share connected to and movable with said section, 5 coöperating means upon the beam and section for normally holding the section in alinement with the beam, said means being shiftable to release the section when the share contacts with an unyielding obstruction, soil engaging means supported in front 10 of the share, means operated by the section when released, for bearing downwardly on said soil engaging means to elevate the beam and share, and means for automatically holding the beam and soil engaging means 15 against relative movement while the share is elevated.
4. A plow including a beam, a section pivotally connected thereto and movable upwardly relative to the beam, a plow share connected to and movable with said section, 20 coöperating means upon the beam and section for normally holding the section in alinement with the beam, said means being shiftable to release the section when the share contacts with an unyielding obstruction, soil engaging means supported in front 25 of the share, means operated by the section when released, for bearing downwardly on said soil engaging means to elevate the beam and share, and means for automatically lowering the section and share upon passing over the obstruction.
5. A plow including a beam, a section pivotally connected thereto and movable upwardly relative to the beam, a plow share connected to and movable with said section, 30 coöperating means upon the beam and section for normally holding the section in alinement with the beam, said means being shiftable to release the section when the share contacts with an unyielding obstruction, soil engaging means supported in front 35 of the share, means operated by the section when released, for bearing downwardly on said soil engaging means to elevate the beam and share, and means for automatically lowering the section and share upon passing over the obstruction.
6. The combination with a beam, of a section pivotally connected thereto and adapted to swing upwardly, a plow share connected to the section and adapted, when brought 40 against an obstruction, to swing the section upwardly relative to the beam, means for normally holding the section in alinement with the beam, a soil engaging element pivotally connected to the beam in front of the share, 45 means operated by the section during its upward movement for shifting said element to elevate the beam during the elevation of the share.
7. The combination with a beam, of a section pivotally connected thereto and adapted to swing upwardly, a plow share connected to the section and adapted, when brought 50 against an obstruction, to swing the section upwardly relative to the beam, means for normally holding the section in alinement with the beam, a soil engaging element pivotally connected to the beam in front of the share, 55 means operated by the section during its upward movement for shifting said element to elevate the beam during the elevation of the share, a ratchet bar upon the beam, a pawl movable with the soil engaging element for engaging said bar to lock the element against movement relative to the beam, and means operated by the share when gravitating to normal position after 60 passing over the obstruction, for releasing the pawl from the ratchet bar and unlocking the soil engaging element.
8. The combination with a beam and a beam section hingedly connected thereto, of a share carried by said section and movable therewith, a beam elevating element extending downwardly from the beam and in front of the share, an equalizer bar connected to said element, means for transmitting motion from the section to the bar to elevate the beam when the section is raised relative to the beam by the contact of the share with an unyielding obstruction, and 65 manually operated means for shifting the equalizer bar to adjust said element.
9. The combination with a beam and a beam section hingedly connected thereto, of a share carried by said section and movable therewith, a beam elevating element extending downwardly from the beam and in front of the share, an equalizer bar connected to said element, means for transmitting motion from the section to the bar to 70 actuate said element and elevate the beam when the share contacts with an obstruction, means for locking the elevated beam to the elevating element, said section and share being shiftable downwardly to normal position when the obstruction is passed, 75 and means carried by said section for unlocking the actuating element when said section is returned to normal position relative to the beam.
10. The combination with a plow beam and a section hingedly connected thereto, of a share carried by said section and adapted to elevate it when the share contacts with an obstruction, means for holding said section in alinement with the beam, 80 a beam elevating element supported in the path of the share, an equalizer bar fulcrumed between its ends upon said element, coöperating means upon said element and the beam for locking the element to the 85
11. The combination with a beam, of a section pivotally connected thereto and adapted to swing upwardly, a plow share connected to the section and adapted, when brought 90 against an obstruction, to swing the section upwardly relative to the beam, means for normally holding the section in alinement with the beam, a soil engaging element pivotally connected to the beam in front of the share, 95 means operated by the section during its upward movement for shifting said element to elevate the beam during the elevation of the share, a ratchet bar upon the beam, a pawl movable with the soil engaging element for engaging said bar to lock the element against movement relative to the beam, and means operated by the share when gravitating to normal position after 100 passing over the obstruction, for releasing the pawl from the ratchet bar and unlocking the soil engaging element.
12. The combination with a beam and a beam section hingedly connected thereto, of a share carried by said section and movable therewith, a beam elevating element extending downwardly from the beam and in front of the share, an equalizer bar connected to said element, means for transmitting motion from the section to the bar to 105 actuate said element and elevate the beam when the share contacts with an obstruction, means for locking the elevated beam to the elevating element, said section and share being shiftable downwardly to normal position when the obstruction is passed, 110 and means carried by said section for unlocking the actuating element when said section is returned to normal position relative to the beam.
13. The combination with a beam, of a section pivotally connected thereto and adapted to swing upwardly, a plow share connected to the section and adapted, when brought 115 against an obstruction, to swing the section upwardly relative to the beam, means for normally holding the section in alinement with the beam, a soil engaging element pivotally connected to the beam in front of the share, 120 means operated by the section during its upward movement for shifting said element to elevate the beam during the elevation of the share, a ratchet bar upon the beam, a pawl movable with the soil engaging element for engaging said bar to lock the element against movement relative to the beam, and means operated by the share when gravitating to normal position after 125 passing over the obstruction, for releasing the pawl from the ratchet bar and unlocking the soil engaging element.
14. The combination with a beam, of a section pivotally connected thereto and adapted to swing upwardly, a plow share connected to the section and adapted, when brought 130 against an obstruction, to swing the section upwardly relative to the beam, means for normally holding the section in alinement with the beam, a soil engaging element pivotally connected to the beam in front of the share, and means operated by the section during its upward movement for shifting said element to elevate the beam during the elevation of the share.

beam when the beam is elevated, means operated by the upwardly moving section for shifting the equalizer to actuate the said element, a lever, a connection between the lever and equalizer, and means carried by the hinged section for unlocking the elevating element when said section is returned to normal position.

11. The combination with a plow structure including a beam, and a share movably connected thereto, of means operated by the share when moved against an obstruction for elevating the share and the beam and carrying the share over the obstruction.

12. The combination with a plow structure including a beam and a share movably connected thereto, of means operated by the share when brought against an obstruction for elevating the share and the beam to pass over the obstruction, and means for locking the beam in raised position.

13. The combination with a plow structure including a beam, and a share movably connected thereto, of means operated by the share when moved against an obstruction for elevating the share relative to the beam and for elevating the beam, and means for locking the beam in raised position, said share being movable downwardly independently of the locking means after passing over the obstruction.

14. The combination with a plow structure including a beam, and a share movably connected thereto, of means operated by the share when moved against an obstruction for elevating the share relative to the beam and for elevating the beam, means for locking the beam in raised position, said share being movable downwardly independently of the locking means after passing the obstruction, and means operated by lowering of the share for releasing the locking means.

45 15. A plow including a beam, a section

pivottally connected thereto and movable relative to the beam, a plow share connected to and movable with said section, coöperating means upon the beam and section for normally holding the section in alinement with the beam, said holding means being shiftable to release the section when the share contacts with an unyielding obstruction, and means supported in front of the share and shiftable by the section, when released, for elevating the beam and share.

16. A plow including a beam, a section pivotally connected thereto and movable relative to the beam, a plow share connected to and movable with said section, coöperating means upon the beam and section for normally holding the section in alinement with the beam, said means being shiftable to release the section when the share contacts with an unyielding obstruction, soil engaging means supported in front of the share, means operated by the section when released, for bearing downwardly on said soil engaging means to elevate the beam and share.

17. The combination with a beam, of a section pivotally connected thereto and adapted to swing, a plow share connected to the section and adapted, when brought against an obstruction, to swing the section relative to the beam, means for normally holding the section in alinement with the beam, a soil engaging element pivotally connected to the beam in front of the share, and means operated by the section during its swing for shifting said element to elevate the beam during the elevation of the share.

In testimony that I claim the foregoing as my own, I have hereto affixed my signature in the presence of two witnesses.
